JOHN P. HEBENDAHL, OF ELIZABETH, NEW JERSEY.

SUPPORTING-BRACKET FOR ELECTRIC LIGHTS.

952,521.

Specification of Letters Patent. Patented Mar. 22, 1910.

Application filed October 11, 1909. Serial No. 522,104.

To all whom it may concern:

Be it known that I, JOHN P. HEBENDAHL, a citizen of the United States, residing at Elizabeth, in the county of Union and State of New Jersey, have invented certain new and useful Improvements in Supporting-Brackets for Electric Lights; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to a bracket for raising and sustaining an article, and is particularly adapted for electric lights, the arm taking the weight from the flexible raising or elevating means so that the rope that is usually employed to lift and hold the lamp is released of the strain when the lamp or the object to be held has been secured in the sustaining means.

The invention provides for an arm that is adjustable vertically on the pole to which the lamp is to be attached, and also provides for a casing on the end of the arm which can be made substantially parallel with the ground, or level, no matter how much the arm is elevated or depressed.

Another object of the invention is to provide means for varying the distance between the pulley, within the outer casing over which the flexible strand passes, and the sustaining means in the casing so that a double rope for elevating the lamp, or a single rope for the same purpose, can be used. This can be accomplished by either moving the pulley toward the sustaining means or forming the sustaining means with means for moving it toward and from the pulley if the pulley is stationary.

The invention is illustrated in the accompanying drawings, in which—

Figure 1 is a side view showing a part of the bracket and the outer casing in section. Fig. 2 is a view of a plate with means for attaching the same to the pole and means whereby the bracket can be attached to the plate. Fig. 3 is a section on line 3, 3, in Fig. 1. Fig. 4 is a section on line 4, 4, in Fig. 1, and Fig. 5 is a section on line 5, in Fig. 1. Fig. 6 is a view of half of the casing with a single rope to support the elec-

tric light. Fig. 7 is a section of the hook employed in the construction shown in Fig. 6. Fig. 8 is a view of half of the casing and a portion of the tube with the pulley stationary and the retaining means arranged so that it is adjustable. Fig. 9 is an enlarged section on line 9, 9, in Fig. 8.

The device is preferably fastened to any usual form of pole 10 against which the plate 11 is bolted or otherwise secured, the plate having a tapered and dove-tailed slot 12 into which is fitted the two half sections 13 having the dove-tailed portions 15 to fit in the slot 12. The half sections 13 are fastened together by a bolt 14 and serve to support a pulley 16, the axle 17 of which also acts as the pivot for the outer half sections 18 which fit over the half sections 13 and thereby form a knuckle-joint whereby the hollow arm or tube 19 can be swung to adjust it to the desired position irrespective of the pole, that is, it can be made level if the pole is made out of plumb, or if the pole is perpendicular it can be put at an angle to meet conditions. Projecting down from the half sections 13 is a tube 20 which can be dispensed with, but is preferably used to more positively guide the rope. The end of the tube 19 can be provided with the housing 21 which is composed of half sections, as shown particularly in Fig. 4. The housing is connected, by a tie-rod or rods 22, with the pole so as to more firmly support the weight of the device. Within the housing is arranged a casing 23, which casing is formed of half sections as shown in Figs. 4 and 5, the casing being adapted to swing in the housing by a suitable pivotal connection, such as a bolt, but preferably by having the projections 24, on the plates forming the two sides of the casing, fitted in the recess portions 25 on the inner face of the housing. This permits the casing to be maintained or adjusted in a horizontal position no matter at what angle the tube 19 is placed, this adjustment being possible by means of the bolt 26 fitting through any of the perforations 27 in the housing and through a perforation in the two half sections of the casing, the perforations 27 being adapted to be placed in or out of register with the perforation in the casing, as will be understood.

The casing is provided with a top portion 28 which forms a cover to prevent snow and rain from entering to rust the parts or to

rot the rope, and the casing also has front flanges 29 that come together to form a closed end, but leaving the opening 30 near the top edge of the front so that the knot 31, of a suitable cord or flexible strand, can be placed in the recess, and the rope or cable passing out through the opening 32 into the casing runs through a pulley 33 having a hook 34 or similar means for supporting the electric light 35, or any other similar object. The pulley is provided with side plates 36 from which project the pins 37, one on each side, the inner faces of the two side plates of the casing being provided with a channel 15 that places the curved surface 38 in the path of the pins 37 as they ride up, and forces the pins away from the pulley 39, over which the rope 40 passes, until the pins snap over the hook 41 and rest in the depression 42 20 which acts as a sustaining means, and when the pin snaps over beyond the point 41 it rests against the point 43 which, with the point 41, makes a forked structure with the recess 42 between them into which the pins 37 rest to sustain the weight. When the lamp is to be lowered the rope is again pulled, the pins 37 will bear against the point 43 of the forked portion, and when they go beyond the point 43 they will snap 30 over into the channel 44 and then when they are let down they ride over the surface 45 and pass out of the channel at 46. This makes a substantially M-shaped passage into and out of which the supporting means, 35 which is set in the sustaining means, passes, resting intermediate of its passage when the tension on the flexible strand is relaxed.

The structure previously described is that illustrated in Fig. 1, but I may use but a single rope 40 as shown in Fig. 6, the end of the rope instead of passing over a pulley and up to the casing again, as in Fig. 1, simply passing over the pulley 39 and having its end passed down through a bar 47 45 which is provided with a socket 48 into which the knot 49 of the rope 40 can be placed, the bar being preferably square and having a hook 50 on its lower end for supporting the light 35. The square bar 49 has, on each face, a pin 51 so that no matter how the rope twists it will ride up in the casing with a pair of the pins in position to be engaged by the recess 42. The operation of seating and unseating the supporting means in the restraining means is similar to that shown in Fig. 1. The casing is shown in Fig. 6 with the housing left off, and it will be seen from this view that the recess 30, with the opening 52 on its top, forms a means for suspending the casing on a cable or wire over a passage way, if desired, by running the cable or wire through the recess 30 and through the opening 52, and allowing the top edge 28 of the casing to rest thereon. It will be noted that if a single

strand or rope, as shown in Fig. 6, were suspended from the position of the pulley in Fig. 1, when the supporting means, such as the bar 47, was raised it would not be in the path of the curved surface 38 of the casing. To overcome this and to properly place the pulley, I make the pulley adjustable toward and from the sustaining means by placing the pulley 39, with its axle 40 projecting from each side thereof, in the slots 41^a, a slot 75 being placed on the inner surface of each of the side plates of the casing, the slots being made in the shape of an inverted U so that the pulley can be shifted, when the weight is off of it, by simply passing it over the curved portion of the slot 41^a to bring it to the desired position, moving it back toward the rear of the casing when the double rope shown in Fig. 1 is to be used, and moving it closer up to the sustaining means when the single rope shown in Fig. 6 is used. This makes it possible to put any kind of a tool up between the side plates of the casing and take the weight from the pulley and lift the pulley and shift it to its proper place. 90 Instead of moving the pulley toward the sustaining means I may make the sustaining means movable toward and from the pulley, this being shown more particularly in Figs. 8 and 9. In these views I illustrate the casing 23 fastened to the tube 19 so that it is not adjustable, and I make the sustaining means with the substantially M-shaped passage therein, formed of two sections 52 which are pivoted at 53 by means of the bolt 100 54, which bolt can fit in any of the holes 55, these holes being of any number, but it is thought that two sets in line are sufficient to make the adjustment from the pulley 56 to meet the conditions, when either one or 105 two strands of the rope are used to hoist the weight to be suspended. The sustaining means takes the nature of a latch in Figs. 8 and 9, swinging in its place to move itself when it grasps the supporting means, and 110 snapping into place by means of its pivotal connection, instead of the supported weight being moved out of its path of travel to be caught.

In the structure shown in Fig. 4 I provide the lugs 57, and in the structure shown in Fig. 9 I provide the lugs 58 adjacent to the top edge of the pulleys in each of the respective constructions so that the rope cannot ride from the pulley and get jammed 120 between the pulley and the casing, and is also held in place so as to make the operation of the device easy.

Having thus described my invention, what I claim is:

1. A bracket comprising a casing, a pulley in the casing, a restraining means in the casing, a flexible strand passing over the pulley, a supporting means on the end of the strand adapted to be seated in the restraining 130

means, and means for varying the distance between the pulley and the restraining means.

5 2. A bracket comprising a casing, a pulley in the casing, a rope passing over the pulley, a restraining means in the casing, a supporting means, and means for varying the distance between the pulley and the restraining means whereby the restraining means will 10 be in the path of the supporting means when the rope is pulled to hoist the supporting means, when the rope is fastened to the supporting means or when the rope is passed through the supporting means with the end 15 of the rope attached to the casing.

3. A bracket comprising a casing, a pulley in the casing, a substantially M-shaped passage, a rope on the pulley, a supporting means on the rope adapted to be suspended 20 in the passage, and means for varying the distance between the passage and the pulley.

4. A bracket comprising a casing, a pulley in the casing, a substantially M-shaped passage in the casing, a rope on the pulley, and supporting means on the rope adapted 25 to be suspended in the passage, the casing having on its opposite walls an inverted U-shaped slot, the ends of the slots receiving the axle of the pulley whereby the distance 30 between the pulley and the passage can be varied.

5. A bracket comprising a casing, a pulley in the casing, a restraining means in the casing, a pulley in the casing, a rope on the pulley, and a supporting means adapted 35 to be suspended by the restraining means and raised and lowered by the rope, the casing having on its opposite walls an inverted U-shaped slot, the ends of the slots receiving 40 the axle of the pulley whereby the distance between the pulley and the restraining means can be varied.

6. A bracket comprising a casing open at the bottom and having means for securing 45 the end of a rope thereto, a pulley in the casing, a rope on the pulley, a restraining means in the casing, a supporting means adapted to be raised and lowered by the rope and suspended by the restraining means, 50 and means for supporting the pulley in the casing at various distances from the restraining means.

7. A bracket comprising an arm, means for securing the arm to a pole, a casing, 55 means for securing the casing to the end of the arm, means for adjusting the casing on the arm whereby it can be level, the casing being open at the bottom, a restraining means in the casing, a pulley in the casing, 60 a rope passing over the pulley, and a supporting means adapted to be engaged by the restraining means and to be raised and lowered by the rope.

8. A bracket comprising an arm, means 65 for securing the arm to a pole, a casing,

means for securing the casing to the end of the arm, means for adjusting the casing on the arm whereby it can be level, the casing being open at the bottom, a restraining means in the casing, a pulley in the casing, 70 a rope passing over the pulley, a supporting means adapted to be engaged by the restraining means and to be raised and lowered by the rope, and means for varying the distance between the pulley and the restraining means.

9. A bracket comprising an arm, means for securing the arm to a pole, the arm being adapted to swing vertically, a casing, 80 means for pivotally securing the casing on the arm, means for securing the casing in its adjusted position, the casing being open at the bottom, a restraining means in the casing, a pulley in the casing, a supporting means adapted to be suspended in the restraining means and adapted to be raised and lowered by the rope, and means for varying the distance between the restraining 85 means and the pulley.

10. A bracket comprising an arm, means 90 for securing the arm to a pole, the arm being adapted to swing vertically, a casing, means for pivotally securing the casing on the arm, means for securing the casing in its adjusted position, the casing being open 95 at the bottom, a restraining means in the casing, a pulley in the casing, a rope on the pulley, and a supporting means adapted to be suspended in the restraining means and adapted to be raised and lowered by the 100 rope, the casing having on its inner walls inverted U-shaped slots to receive the axle of the pulley whereby the pulley can be shifted from one end of the slot to the other to vary its distance from the restraining 105 means.

11. A bracket comprising an arm, a knuckle-joint for securing the arm to a pole, a casing, means for pivotally securing the casing to the end of the arm, means for securing the casing in its adjusted positions so that it can be maintained level when the arm is swung, a pulley in the casing, a rope on the pulley, the casing having a substantially 110 M-shaped passage, and a supporting 115 means adapted to be suspended in the passage and raised and lowered by the rope.

12. A bracket comprising an arm, half sections secured to the arm on one end, half sections to fit in the half sections on the arm, 120 a pin to pass through the half sections whereby they are formed into a knuckle-joint, a pulley on the pin, the half sections opposed to those on the arm having tapered dove-tailed portions, a plate having a tapered dove-tailed slot to receive the dove-tailed portions, means for securing the plate to a support, a casing on the free end of the arm, a restraining means in the casing, a 125 pulley in the casing, a rope passing over the 130

pulley in the casing and the pulley in the knuckle-joint, and a supporting means adapted to be raised and lowered by the rope and adapted to be suspended in the restraining means.

13. A bracket comprising an arm, half sections secured to the arm on one end, half sections to fit in the half sections on the arm, a pin to pass through the half sections whereby they are formed into a knuckle-joint, a pulley on the pin, the half sections opposed to those on the arm having tapered dove-tailed portions, a plate having a tapered dove-tailed slot to receive the dove-tailed portions, means for securing the plate to a support, a casing on the free end of the arm, a restraining means in the casing, a pulley in the casing, a rope passing over the pulley in the casing and the pulley in the knuckle-joint, a supporting means adapted to be raised and lowered by the rope and adapted to be suspended in the restraining means, and means for varying the distance between the pulley and the restraining means.

14. A bracket comprising a hollow arm, means for securing the arm to a support whereby the arm can be swung, a housing on the free end of the arm, a casing secured in the housing and in pivotal relation thereto, means for securing the housing and the casing in different adjusted positions, the

casing having a substantially M-shaped passage, a pulley in the casing, a rope on the pulley, a supporting means adapted to be raised and lowered by the rope and adapted to enter the passage to be suspended therein, and means for varying the distance between the pulley and the passage.

15. A bracket comprising a hollow arm, a knuckle-joint for securing the hollow arm to the support, a housing on the free end of the arm, a casing composed of side plates arranged in the housing and adapted to pivotally swing therein, means for securing the casing to the housing in its adjusted positions, the casing being open at the bottom, the side plates of the casing having alined M-shaped passages, a supporting means adapted to be raised and lowered by a rope, and having pins to enter the passages and adapted to be supported therein when the tension on the rope is relaxed, the side plates having inverted U-shaped slots to receive the axle of the pulley, the ends of the slots being arranged to support the axle at different distances from the passages.

In testimony, that I claim the foregoing, I have hereunto set my hand this 8th day of October 1909.

JOHN P. HEBENDAHL.
